UNITED STATES PATENT OFFICE.

LORENZO M. MULET, OF SAN JUAN, PORTO RICO.

CONTINUOUS CENTRIFUGAL SEPARATOR.

1,309,651.

Specification of Letters Patent.

Patented July 15, 1919.

Application filed May 9, 1917. Serial No. 167,528.

To all whom it may concern:

Be it known that I, LORENZO M. MULET, a citizen of the United States, residing at San Juan, in the county of San Juan, Territory of Porto Rico, have invented certain new and useful Improvements in Continuous Centrifugal Separators; and I do hereby declare the following to be a full, clear, and exact description of the invention, such as 10 will enable others skilled in the art to which it appertains to make and use the same.

This invention relates to centrifugal separators and has special reference to the type of centrifugal separator which is used for 15 separating solid material from contained liquid, such as sugar from molasses.

Heretofore in the operation of centrifugal separators it has been found that these devices are the most expensive devices used on 20 a sugar plantation. The reason for this is that the ordinary centrifugal separator is charged with the wet sugar through an opening in the top, the separator casing having an opening in the bottom normally 25 closed by a plug. The separator is then started to work and the sugar collects on the separating wall in a layer, the molasses flowing through the perforations in the wall and being collected in a suitable trough between the separating wall and the casing. In 30 order to get rid of the sugar thus separated it is necessary to stop the separator. The operator then takes a paddle and scrapes off all the sugar from the wall so that it falls in the bottom of the casing, previously removing the plug from the opening in the center of the casing bottom. He then pushes the sugar toward the center and down the opening until he has gotten rid of as much 35 sugar as possible down this opening. This operation naturally requires a very considerable time and during this time the separator is idle and it is found in practice that the time consumed is at least equal to the 40 time required for the separation of the molasses from the sugar. Thus on a plantation where the full capacity of a separator is needed, that is to say the capacity of a separator running constantly and without clean- 45 out interruptions, it is essential that there be two separators one of which can remain idle while the other is being used for the separating process. This of course entails additional floor space, driving machinery and 50 labor.

The principal object of the present in-

vention is to provide a centrifugal separator which will clear itself automatically and continuously of the separator sugar.

It is also found in the use of an ordinary 60 type of separator that the openings in the screen become clogged with the sugar and it frequently happens that these openings have to be punched out in order to provide for the escape of the molasses. 65

A second important object of the present invention is to provide a separator wherein the action of the separator itself will be such as to loosen the clogs of sugar in the 70 openings of the separator screen or wall and thus eliminate the necessity of cleaning out these openings.

With the above and other objects in view, such as will be hereinafter apparent the invention consists in general of certain novel 75 details of construction and combinations of parts hereinafter fully described, illustrated in the accompanying drawings, and specifically claimed.

In the accompanying drawings, like characters of reference indicate like parts in the several views, and:

Fig. 1 is a vertical medium section taken through a separator constructed in accordance with this invention.

Fig. 2 is a view showing horizontal sections on different planes, one third of the view being a section on the line $x-x$ of Fig. 1, and a second part of the view being a section on the line $y-y$ of Fig. 1.

Fig. 3 is a detail partial bottom plan view of a separator with the receiving hopper removed.

Fig. 4 is a section on the line 4-4 of Fig. 1.

Fig. 5 is a section on the line 5-5 of Fig. 1.

Fig. 6 is a section on the line 6-6 of Fig. 1.

Fig. 7 is a section on the line 7-7 of Fig. 1.

Fig. 8 is a detail perspective showing the manner of securing certain guides used herewith.

In the drawings herewith there has been 105 illustrated one preferred embodiment of the invention which is particularly adapted for use in the separation of molasses from sugar. It is not, however, to be understood that the device is only to be used for the separation of 110 molasses from sugar but it will be obvious that the same machine or a machine differ-

ing from this machine only in its details of construction may be used for the separation of various other substances into their component, solid and liquid parts.

5 In the embodiment herein illustrated there has been shown a shaft 10 which may be termed the main or driving shaft and this shaft is supported at its upper end in a suitable bearing which is not deemed necessary 10 to show. Suitable means are provided on this shaft for supplying power thereto and as typical of such means there has been disclosed a belt pulley 11 although this means is to be taken as merely typical and any suitable manner of driving the shaft 10 may be used.

Suspended from the upper bearing by means of rods 12 is a casing or housing 13 which is preferably of substantial frustoconical form and has on its inside at its lower edge a trough 14 for the reception of molasses after separation from the sugar. This trough extends entirely around the device and is preferably so pitched with respect to the horizontal that the molasses will run down toward an outlet 15.

Secured to the trough 14 are the outer ends of spider arms 16 which unite in a hub 17. Within this hub 17 is located a bearing 20 box 18 provided with an anti-friction liner 19 and having in its lower end a closure 22 whereon rests an end thrust ball 21. The lower end of the shaft 10 is reduced as at 22 and this reduced end is received in the bearings just described so that by this means both the upper and lower ends of the shaft are supported in bearings.

Fixed on the shaft 10 at the upper part of the casing or housing 13 is a spider hub 22' 40 from which radiate spider arms 23 having upturned ends 24. Mounted on these upturned ends and securely fastened thereto is a ring 25 whereon are arranged the spaced bearings 26, the bearings being disposed in pairs and the pairs equally spaced entirely around the ring. In these bearings 26 are journaled short shaft sections 27 whereon are mounted sprockets 28.

A little below the center of the casing is 50 provided a second spider hub 29 from which radiate the arms 30 having downwardly turned ends 31. Through these downwardly turned ends 31 are securely fixed brackets 32 which carry a lower ring 33. On this lower ring 33 are provided spaced pairs of bearings 34, the bearings on the lower ring being disposed directly below the bearings on the upper ring and, in these bearings 34 are mounted the shaft sections 35. Furthermore 55 there are disposed around the ring 33 three pairs of bearings 36, these bearings being so arranged that the pairs are equally spaced and in these latter bearings are supported shaft sections 37. Mounted on these shaft 60 sections are worm wheels 38 respectively.

Between each pair of the bearings 34 there is mounted on the respective shaft section 35 a sprocket wheel 39 which is connected by means of a sprocket chain 40 to a corresponding one of the sprockets 28 above and 70 in the same plane therewith. In order to effect simultaneous rotation of all of the shaft sections 35 and 37 they are connected by means of universal joints 41.

Now from the foregoing it will be seen 75 that if one of the shaft sections 37 be revolved by the revolution of its worm wheel then all of the sections 37 and 35 will simultaneously revolve and thus all of the sprocket chains will be simultaneously 80 driven.

In order to effect the driving of the worm wheels there is provided on each of the arms 30 a bearing 42 wherein is journaled a shaft 43 carrying at its outer end a worm 44 which 85 meshes with a respective worm wheel 38. On the inner end of each shaft 43 is a beveled gear 45 which meshes with a beveled gear 46 revolvably mounted on the shaft 10. Fixed in one of the arms 16 is a stub shaft 47 90 whereon is revolvably mounted a gear 48 which meshes with a gear 49 fixed on the hub 50 of the gear 46. Connected to the gear 48 is a gear 51, also mounted on the shaft 47 and this gear 51 meshes with a gear 52 which is keyed upon the shaft 10. From an inspection of Fig. 1 it will be seen that the diameter of the gear 52 is greater than the diameter of the gear 49 and consequently the diameter of the gear 51 is less than the 100 diameter of the gear 48. By means of this arrangement the rotation of the shaft 10 will cause rotation of the rings 25 and 33 and thus of the shaft 43 about the axis of said shaft 10. At the same time the gear 105 52 will revolve as fast as the shaft 10 but the revolution of this gear 52 will cause revolution of the gear 51 which in turn will revolve the gear 48. The gear 49 which meshes with the gear 48 will thus revolve 110 in the same direction as the gear 52 but at a higher rate of speed, the difference being only slight. Now the revolution of this gear 49 is communicated to the shaft 43 through the gears 46 and 45 so that consequently these shafts will revolve and in their revolution will rotate the lower sprockets 39 and cause travel of the inner portions of the chains downward and the outer portions of the chains upward when 120 the shaft 10 is revolved in the proper direction for separation.

In order to separate the sugar from molasses there is provided a cylinder 54 which extends vertically across the inner flanges 125 of the rings 25 and 33, to which it is secured, and is formed of a perforated sheet of metal through which the molasses may pass as it is carried thereacross by a series of endless carriers or bands. On each of the sprocket 130

chains is provided an endless foraminous band 53 and this band is preferably made of flexible steel or other like material. These bands inclose the perforated cylinder 54 and are arranged in three sets and each set is separated from the adjacent set by a slight space so that the arms 23 and brackets 32 can pass between the adjacent edges of the sets. In order to prevent the passage of sugar through the gaps thus left there are formed in the cylinder 54 between the opposing edges of these sets certain ridges or stops 54' which close in these spaces.

Furthermore the plates 53 are arranged so that one edge of each plate overlaps the adjacent edge of the next plate as can be clearly seen by reference to Figs. 2 and 3. The purpose of this is to prevent any sliding of the sugar which may take place to be free and uninterrupted and to prevent the lodging of such sugar against the edges of the plates, the overlapping being so arranged that as the shaft is revolved in the direction of the arrow in Fig. 2 the rear edge of each plate will be the overlapping edge.

The outer portions of these bands 53 are supported at their edges by guides 55 which extend vertically of the machine, being carried on the respective upper and lower rings and securely fixed thereto. From an inspection of Fig. 2 it will be observed that these guides 55 have their adjacent edges spaced and the purpose of this spacing can be best observed by an inspection of Fig. 2 wherein the short arrows indicate the route taken by the molasses in passing through the separator screens or bands.

On the upper end of the hub 22' is a conical flange 56 and mounted on this flange 56 is a conical spreader plate 57. At 58 is a receiving hopper which surrounds the shaft 10 and is open at the bottom and from the bottom portion of this hopper flares outwardly a frusto-conical guard plate 59, the pitch of this plate being greater than the pitch of the plate 57 and the edges of the two plates 59 and 57 being closely spaced so that together they form a distributing slit which lies close to the endless band 53.

Now as the sugar is poured into the hopper 58 the rapid revolution of the plate 57 will cause the sugar to fly off of this plate between this and the plate 59 by centrifugal action and the wet sugar flying off of the plate 57 will strike against the upper of the inner portions of the endless bands and by action of the gearing before referred to this sugar will be carried downward. During its passage downward on the inner portions of these bands the centrifugal action of the machine will cause the flow of the molasses through the perforations in the endless bands and the cylinder 54 and then across the spaces between the guide members as shown in Fig. 2 so that it will strike the cas-

ing 18, which is stationary, and flow down this casing to the trough 14 and thence outward through the delivery spout 15, being collected in any suitable receptacle.

Mounted below the casing 13 is a receiving hopper or bin 60 the upper edge of which lies in such position that any material thrown off the lower bights of the endless bands by centrifugal action will strike this upper edge and fall down toward the bottom of the hopper.

As before set forth the sugar is carried downward by the inner sides of the endless bands and in its downward motion adheres closely to these bands, in fact forming a cake 80 on the bands. When the bands reach the lower sprocket they will be bent by the action of the sprocket chains around these sprockets and will thus crack off the adhered sugar and at the same time the bending will 85 effect loosening of any plugs of sugar which may be in the perforations of the bands. Upon reaching almost the bottom point of the band the centrifugal action of the rapidly running machine will throw the sugar, 90 now loosened, off of these bands against the upper edge of the inner surface of the hopper 60 so that the dried sugar will fall down and collect in said hopper.

Now from the foregoing it will be seen 95 that the operation may be continued since it is merely necessary to keep the hopper 58 charged with sugar which will automatically be spread on the upper parts of the inner portions of the endless bands and then be 100 dried by the centrifugal action and automatically thrown off of the lower ends of said bands into the receiving hopper. Thus, the separator may be run continuously without any stops whatever for cleaning out the 105 mass of the sugar or for removing the plugs from the perforations in the bands.

There has been provided a simple and efficient device of the kind described and for the purpose specified.

It is obvious that many minor changes may be made in the form and construction of the invention without departing from the material principles thereof. It is not therefore desired to confine the invention to the 115 exact form herein shown and described but it is wished to include all such as properly come within the scope claimed.

Having thus described the invention, what is claimed as new, is:—

1. The combination with a separator casing; of a shaft rotatably mounted concentric of said casing, spiders fixed on said shaft, rotatable carrier wheels supported by said spiders, endless foraminous belts carried by said wheels inwardly of the edges of the belts, said belts being arranged in overlapping relation, means to rotate said shaft, and means to drive certain of said wheels in timed relation to said shaft.

2. The combination with a separator casing; of a shaft rotatably mounted concentric of the casing, an upper and a lower spider fixed on said shaft, sprockets supported rotatably by the spiders to form upper and lower series, the sprockets of one series being connected whereby all the sprockets of the connected series may rotate simultaneously, sprocket chains connecting the sprockets of one series with the sprockets of the other series, endless foraminous bands fixed to said chains inwardly of the side edges of the bands with their inner side portions in overlapping relation, means to rotate the shaft, and means to rotate the sprockets in timed relation to the shaft. 70
3. The combination with a separator casing, of a shaft rotatably mounted concentric of the casing, an upper and a lower spider, 20 bearings supported by said spiders and forming upper and lower circular series, a sectional shaft having its sections connected by universal joints and journaled in the bearings of one series, other shaft sections 25 journaled in the bearings of the other series, sprockets fixed on said sections, chains connecting the sprockets of the upper series with the sprockets of the lower series, endless foraminous bands carried by said chains 30 and arranged in groups to form composite continuous inner separating wall sections, wall members connecting and overlapping the composite wall sections, means to drive said first shaft and gearing connecting the 35 first shaft with the universally jointed shaft and including a gear having an axis fixed with relation to the movement of said first shaft. 40
4. The combination with a separator casing, of a shaft rotatably mounted concentric of the casing, an upper and a lower spider, 45 bearings supported by said spiders and forming upper and lower circular series, a sectional shaft having its sections connected by universal joints and journaled in the bearings of one series, other shaft sections journaled in the bearings of the other series, sprockets fixed on said sections, chains connecting the sprockets of the upper series 50 with the sprockets of the lower series, endless foraminous bands carried by said chains and arranged to form a continuous inner separating wall, means to drive said first shaft and gearing connecting the first shaft 55 with the universally jointed shaft and including a gear fixed on said first shaft, a gear rotatably mounted on said first shaft and having a different pitch diameter than the first gear, a fixed shaft, a double gear 60 mounted on the fixed shaft and meshing with the first two gears, a bevel gear connected to the second gear and rotatable therewith, radially aligned bearings on one of the spiders, a shaft journaled in the last 65 mentioned bearings, a bevel gear on said last shaft meshing with the first bevel gear, a worm on said last shaft, and a worm wheel on one of the sections of the universally jointed shaft. 70
5. The combination with a separator casing; of endless foraminous bands arranged parallel to the axis of rotation and forming inner overlapping and outer spaced walls, means to rotate said walls about said axis, 75 means to cause travel of the inner and outer portions of said bands in opposite directions, means to continuously feed material to be dried to the upper parts of said bands and guides with which the spaced edges of the outer walls are movably engaged, disposed to receive and direct molasses from over said edges. 80
6. The combination with a separator casing; of a shaft rotatably mounted concentric of said casing, spiders fixed on said shaft, 85 rotatable carrier wheels supported by said spiders, endless foraminous bands carried by said wheels in overlapping relation, means to rotate said shaft, other means to drive certain of said wheels, and means to continuously feed material to be dried to the 90 upper parts of said bands. 95
7. The combination with a separator casing; of a shaft rotatably mounted concentric of said casing, spiders fixed on said shaft, 95 rotatable carrier wheels supported by said spiders, endless foraminous belts carried by said wheels and arranged to form a continuous inner and an outer wall, means to rotate said shaft, means to drive certain of said 100 wheels in timed relation to said shaft, and means to feed material to be dried to said bands. 105
8. The combination with a separator casing, of a shaft rotatably mounted concentric 105 of the casing, an upper and a lower spider, bearings supported by said spiders and forming upper and lower circular series, a sectional shaft having its sections connected by universal joints and journaled in the bearings of one series, other shaft sections unconnected and journaled in the bearings of the other series, sprockets fixed on said sections, chains connecting the sprockets of the upper series with the sprockets of the lower 110 series, endless foraminous bands carried by said chains in overlapping relation, means to drive said first shaft, gearing connecting the first shaft with the universally jointed, 115 shaft and including a gear having an axis fixed with relation to the movement of said first shaft, and means to feed material to be dried to the upper parts of said bands. 120
9. The combination with a centrifugal separator having a wall including overlapping sections, certain of which are movable; of means to effect movement of successive portions of said wall into position at right angles to the axis of rotation of the separator, means to continuously feed material 125 130

- to be dried to one end of the wall, and an open topped hopper beneath the separator and having its upper edge portion positioned to receive the discharge from the separator.
10. A centrifugal separator comprising a plurality of endless foraminous belts arranged in a circular series and having means for feeding them longitudinally, a driving mechanism for the feeding means including shafts passing between certain of the belts, and a guard disposed to bridge the inter-spaces between the belts having said shafts therebetween, the belts between each pair of shafts having their inner side portions in overlapping relation. 70
11. The combination with a separator casing; of a shaft rotatably mounted concentric of said casing, spiders fixed on said shaft, rotatable carrier wheels supported by said spiders, endless foraminous bands carried by said wheels inwardly of the side edges of the bands and in overlapping relation, means to rotate said shaft, other means to drive certain of said wheels, means to continuously feed material to be dried to the upper parts of said bands, and an open topped hopper beneath the separator and having its upper edge portion surrounding the lower portions of said bands. 75
12. The combination with a separator casing; of a shaft rotatably mounted concentric of said casing, spiders fixed on said shaft, rotatable carrier wheels supported by said spiders, endless foraminous belts carried by said wheels, certain of which belts are in overlapping relation, means to rotate said shaft, means disposed between the unlapped belt edges to drive certain of said wheels in timed relation to said shaft, plates bridging between opposed unlapped belt edges, means to feed material to be dried to the upper parts of said bands, and an open topped hopper beneath the separator and having its upper edge portion surrounding the lower portions of said bands. 80
13. The combination with a separator casing; of endless foraminous bands arranged within the casing to form inner and outer walls, the bands extending parallel to the axis of the casing, means to rotate said bands about said axis, means to cause travel of the inner portions of the bands in one direction and the outer portions of the bands in the opposite direction and transverse their movement of rotation, and guides embracing the portions of the bands forming the outer wall and spaced to provide fluid escape openings. 85
14. The combination with a separator casing; of a shaft rotatably mounted concentric of said casing, spiders fixed on said shaft, rotatable carrier wheels supported by said spiders, endless foraminous belts carried by said wheels and arranged to form a continuous inner and an outer wall, means to rotate said shaft, means to drive certain of said wheels in timed relation to said shaft, and guides embracing the portions of the bands forming the outer wall and spaced to provide fluid escape openings. 90
15. The combination with a separator casing; of a shaft rotatably mounted concentric of the casing, an upper and a lower spider fixed on said shaft, sprockets supported rotatably by the spiders to form upper and lower series, the sprockets of one series being connected whereby all the sprockets of the connected series may rotate simultaneously, sprocket chains connecting the sprockets of one series with the sprockets of the other series, endless foraminous bands fixed to said chains, means to rotate the shaft, means to rotate the sprockets in timed relation to the shaft, and guides embracing the portions of the bands forming the outer wall and spaced to provide fluid escape openings. 95
16. The combination with a separator casing, of a shaft rotatably mounted concentric of the casing, an upper and a lower spider, bearings supported by said spiders and forming upper and lower circular series, a sectional shaft having its sections connected by universal joints and journaled in the bearings of one series, other shaft sections journaled in the bearings of the other series, sprockets fixed on said sections, chains connecting the sprockets of the upper series with the sprockets of the lower series, endless foraminous bands carried by said chains and arranged to form a continuous inner separating wall, means to drive said first shaft, gearing connecting the first shaft with the universally jointed shaft and including a gear having an axis fixed with relation to the movement of said first shaft, and guides embracing the portions of the bands forming the outer wall and spaced to provide fluid escape openings. 100
17. The combination with a separator casing, of a shaft rotatably mounted concentric of the casing; an upper and a lower spider, bearings supported by said spiders and forming upper and lower circular series, a sectional shaft having its sections connected by universal joints and journaled in the bearings of one series, other shaft sections journaled in the bearings of the other series, sprockets fixed on said sections, chains connecting the sprockets of the upper series with the sprockets of the lower series, endless foraminous bands carried by said chains and arranged to form a continuous inner separating wall, means to drive said first shaft and gearing connecting the first shaft with the universally jointed shaft and including a gear fixed on said first shaft, a gear rotatably mounted on said first shaft and having a different pitch diameter than the first gear, a fixed shaft, a double gear mounted on the fixed shaft and meshing 110
18. The combination with a separator casing; of a shaft rotatably mounted concentric of the casing, spiders fixed on said shaft, rotatable carrier wheels supported by said spiders, endless foraminous bands carried by said wheels and arranged to form a continuous inner and an outer wall, means to rotate said shaft, means to drive certain of said wheels in timed relation to said shaft, and guides embracing the portions of the bands forming the outer wall and spaced to provide fluid escape openings. 115
19. The combination with a separator casing; of a shaft rotatably mounted concentric of the casing, an upper and a lower spider, bearings supported by said spiders and forming upper and lower circular series, a sectional shaft having its sections connected by universal joints and journaled in the bearings of one series, other shaft sections journaled in the bearings of the other series, sprockets fixed on said sections, chains connecting the sprockets of the upper series with the sprockets of the lower series, endless foraminous bands carried by said chains and arranged to form a continuous inner separating wall, means to drive said first shaft and gearing connecting the first shaft with the universally jointed shaft and including a gear fixed on said first shaft, a gear rotatably mounted on said first shaft and having a different pitch diameter than the first gear, a fixed shaft, a double gear mounted on the fixed shaft and meshing 120
20. The combination with a separator casing; of a shaft rotatably mounted concentric of the casing, spiders fixed on said shaft, rotatable carrier wheels supported by said spiders, endless foraminous bands carried by said wheels and arranged to form a continuous inner and an outer wall, means to rotate said shaft, means to drive certain of said wheels in timed relation to said shaft, and guides embracing the portions of the bands forming the outer wall and spaced to provide fluid escape openings. 125
21. The combination with a separator casing; of a shaft rotatably mounted concentric of the casing, an upper and a lower spider, bearings supported by said spiders and forming upper and lower circular series, a sectional shaft having its sections connected by universal joints and journaled in the bearings of one series, other shaft sections journaled in the bearings of the other series, sprockets fixed on said sections, chains connecting the sprockets of the upper series with the sprockets of the lower series, endless foraminous bands carried by said chains and arranged to form a continuous inner separating wall, means to drive said first shaft and gearing connecting the first shaft with the universally jointed shaft and including a gear fixed on said first shaft, a gear rotatably mounted on said first shaft and having a different pitch diameter than the first gear, a fixed shaft, a double gear mounted on the fixed shaft and meshing 130

with the first two gears, a bevel gear connected to the second gear and rotatable therewith, radially aligned bearings on one of the spiders, a shaft journaled in the last mentioned bearings, a bevel gear on said last shaft meshing with the first bevel gear, a worm on said last shaft, a worm wheel on one of the sections of the universally jointed shaft, and guides embracing the portions of

the bands forming the outer wall and spaced to provide fluid escape openings.

In testimony whereof, I affix my signature, in the presence of two witnesses.

LORENZO M. MULET.
